FOLDING EXERCISE BOARD

George E. Werner, South Orange, N.J. (% Deeco, Inc.,
225 Belleville Ave., Bloomfield, N.J. 07003)

Filed May 23, 1967, Ser. No. 7,231

Term of patent 14 years

(Cl. D34—5)

FIG. 1

FIG. 2

FIG. 3

FIG. 4

FIG. 5

FIG. 6

FIGURE 1 is a perspective view of the folding exercise board of the present invention.

FIGURE 2 is a right side view thereof.

FIGURE 3 is a front plan view thereof.

FIGURE 4 is a top plan view thereof.

FIGURE 5 is a bottom plan view thereof.

FIGURE 6 is a rear elevational view thereof.

A left side view thereof would be the mirror image of the right side view thereof of FIGURE 2.

The folding exercise board being characterized by the combination on the slant board shown of triangular supports on opposite sides of the lower end of the slant board with a pedal structure pivotally mounted between the apices of the triangular supports substantially as shown.

I claim:

The ornamental design for a folding exercise board, substantially as shown and described.
